UNITED STATES PATENT OFFICE.

ROBERT J. COPELAND, OF TORONTO, ONTARIO, CANADA.

BOOK COVER.

Application filed August 22, 1921. Serial No. 494,193.

To all whom it may concern:

Be it known that I, ROBERT J. COPELAND, a subject of the King of Great Britain, and resident of the city of Toronto, county of 5 York, Province of Ontario, in the Dominion of Canada, have invented certain new and useful Improvements in Book Covers, described in the following specification and illustrated in the accompanying drawings, 10 that form part of the same.

The objects of this invention are, to provide a cover which will withstand the wear and tear of long usage so as to effectively protect the leaves of the book and maintain 15 them in good condition and which will retain a good appearance.

The principal feature of the invention consists in constructing a frame of a tough 20 homogeneous material such as vulcanized fibre and rigidly connecting the members of the frame with a reinforcing sheet material and forming a structure presenting wear resisting edges.

In the drawings Figure 1 is a perspective 25 view of a cover constructed in accordance with this invention.

Figure 2 is a longitudinal sectional view through Figure 1.

Figure 3 is a transverse sectional view 30 through Figure 1.

Figure 4 is a sectional view of a modified structure.

It has been the custom for many years to form the body of the book covers of several 35 ply of what is known as "mill-board" and these are covered with leather or cloth but it has been found that through continued use the layers of material of which the "mill-board" is formed separate and the edges 40 and corners become soft and pulpy and the cover has to be discarded. Further, the covers of large books such as bank ledgers become misshapen and broken across through leaning upon them and metal bindings of various kinds have been resorted to 45 in an effort to lengthen their service.

The present invention overcomes these objectionable features by utilizing a tough and flexible material which will retain its shape 50 and may be readily machined to any desired form enabling the sections to be fitted together and secured to form a strong and durable cover which will present an attractive appearance.

55 In the construction herein shown, a thin sheet 1 of strong tough material such as vul-

canized fibre or sheet steel is cut the desired shape and size and to the edges of this sheet are secured the side and end strips 2 and 3 respectively forming a rigid frame. These 60 strips are formed of material such as vulcanized fibre preferably of a solid section having longitudinal grooves 4 to receive the edges of the sheet 1. The strips when fitted on the sheet 1 are rigidly secured preferably 65 by the rivets 5 which pass through the strips and the sheet.

A back strip 6 is secured at the hinge end of the cover and this is also preferably formed with a groove 7 in the edge to receive 70 the edge of the sheet 1 which is also riveted securely. A groove 8 is formed in the outer edge of the member 6 to receive the hinge member 9.

Filling panels 10 of mill-board or other 75 suitable material are inserted in the panel recesses formed between the fibre edges and these are riveted through the central reinforcing plate 1, thus further stiffening the whole structure. A facing of leather or 80 other suitable material may be secured to the face of the panels 10 and the panels may be slightly depressed if desired so that the facing will be protected from wear by the fibre edge strips. 85

In the form shown in Figure 4 extra reinforcing strips 11 of thin spring steel are arranged to extend longitudinally of the cover, the outer strips fitting in the edge 90 grooves of the side fibre strips 2 and being riveted to the edge strips.

A cover constructed as described is practically indestructible. It is sufficiently flexible to yield under heavy strain but will not crack or break and its sectional reinforced 95 structure ensures its return to its normal shape when the strain is relieved. Further, it will not warp out of shape and the fibre will not become disfigured through long continued use. 100

Another very important feature of this invention is that the material used may be very accurately machined so that the sections will fit together snugly and the assembling may be accomplished very rapidly. 105 The slow and expensive book binding methods of wrapping and gluing as usually practiced are thus eliminated.

What I claim as my invention is:—

1. A book cover comprising a rigid four 110 sided frame of vulcanized fibre having slotted inner edges, a thin sheet of a tough,

strong, homogeneous material extending into the slots in said frame and being rigidly secured therein connecting and reinforcing the members of said frame, and panels of a light and soft material fitted between the members of said frame and covering said reinforcing sheet.

2. A book cover comprising a thin rectangular sheet of vulcanized fibre, a frame of vulcanized fibre having slotted inner edges embracing the four edges of the sheet, rivets binding the slotted edges of the frame to the edges of said sheet, and cardboard panels secured to the sheet and fitting between the inner edges of the frame.

3. A book cover comprising a sheet of thin tough material, edge strips of greater thickness than said sheet grooved to receive said sheet, spring metal strips extending longitudinally of said sheet and extending into said grooves, and rivets securing said edge strips and metal strips to said sheet.

4. A book cover comprising a thin sheet of vulcanized fibre, a frame of vulcanized fibre embracing the edges of said sheet and rigidly connected thereto, and panels of cardboard secured to said sheet within the frame.

ROBERT J. COPELAND.
